EXTRACTION OF AROMATIC HYDROCARBONS WITH ESTERS OF THIOLSULFONIC ACID

William F. Wolff, Park Forest, Ill., and Carl E. Johnson, Griffith, Ind., assignors to Standard Oil Company, Chicago, Ill., a corporation of Indiana

Application August 30, 1951, Serial No. 244,373

9 Claims. (Cl. 260—674)

1

This invention relates to a process for the selective extraction of aromatic hydrocarbons and particularly polycyclic aromatic hydrocarbons from mixtures thereof with other hydrocarbons, for example such mixtures as occur in various unprocessed or unprocessed petroleum oils. Various aromatic hydrocarbons are of value as solvents and for the preparation of resins, plasticizers and various other chemical derivatives; in addition, their removal from various hydrocarbon stocks containing the same may be desired in order to prepare partially dearomatized hydrocarbon stocks for thermal or catalytic cracking, for hydrogenation operations, or for use as heater oils.

A considerable number of selective solvents have been proposed for the removal of polycyclic aromatic hydrocarbons from hydrocarbon stocks containing the same, but heretofore no solvent has been found to be sufficiently desirable for all purposes to retard the further search for improved selective solvents. We have discovered that certain esters of thiolsulfonic acids are surprisingly effective selective solvents for aromatic hydrocarbons and particularly polycyclic aromatics in admixture with other hydrocarbons such as aliphatic or saturated hydrocarbons, notably naturally occurring mixtures such as petroleum oil fractions, coal tar fractions or shale oil fractions. For example, the esters of thiolsulfonic acids are excellent solvents for mono- and dimethylnaphthalenes, mono- and polymethylnaphthalenes and the like. We have further found that said thiolsulfonic esters can be prepared relatively cheaply, have relatively mild corrosive properties permitting their employment in conventional equipment, are characterized by surprisingly low or negligible solubility in the raffinate phase produced by the extraction process, are readily recoverable, and have physical properties which permit their employment as selective extraction solvents for organic sulfur compounds and aromatic hydrocarbons at readily attainable temperatures and pressures. Moreover, the molecular weight and chemical constitution of the thiolsulfonic esters can be varied to obtain "tailor-made" extraction solvents best suited for the particular extraction operations as they arise.

It is an object of this invention to provide a process for the selective extraction of aromatic hydrocarbons, particularly polycyclic aromatics, from their mixtures with other hydrocarbons. Another object of this invention is to provide the art of selective extraction of polycyclic aromatic

hydrocarbons with novel solvents, viz., certain thiolsulfonic esters. An additional object of our invention is to provide solvents for selective extraction processes characterized by high selectivity for polycyclic aromatic hydrocarbons but exhibiting little or no solvent capacity for aliphatic hydrocarbons, particularly saturated hydrocarbons. Yet another object of our invention is to provide the art with novel selective extraction processes and solvent recovery procedures.

These and other objects of our invention will be readily discerned from the ensuing description thereof and from the appended drawing which is a schematic flow sheet illustrating our process.

The novel solvents employed in the selective extraction process of this invention are thiolsulfonic esters containing between 2 and 20 carbon atoms, inclusive, per molecule and having the general formula:

wherein R_1 and R_2 may be the same or different and are selected from the class consisting of hydrocarbon radicals and substituted hydrocarbon radicals. Ordinarily, it is preferred to employ thiolsulfonic esters wherein R_1 and R_2 are unsubstituted hydrocarbon radicals containing no aliphatic unsaturation, i. e., wherein R_1 and R_2 are selected from the class consisting of saturated hydrocarbon radicals and aromatic hydrocarbon radicals. Thus, the hydrocarbon radical may be an alkyl radical, a cycloalkyl radical, a cycloalkyl-alkyl radical, an aralkyl radical, or an aryl, alkaryl or cycloalkyl-aryl radical. The R_1 and R_2 radicals in the above formula may contain negative substituents such as halogen atoms, nitro groups, amino groups or the like.

Examples, given by way of illustration and not necessarily for limitative purposes, of suitable R_1 or R_2 alkyl radicals are: methyl, ethyl, n-propyl, isopropyl, n-butyl, mixtures containing two or more of these, amyl, octyl, nonyl, hexadecyl and octadecyl. Illustrative examples of suitable R_1 or R_2 cycloalkyl radicals include cyclopentyl, methylcyclopentyl, cyclohexyl, methylecyclohexyl, dimethylcyclohexyl, ethylcyclohexyl, ethylcyclopentyl, and endomethylenecyclohexyl (bicyclo [2,2,1] heptyl) and 2-methyl-bicyclo [2,2,1] heptyl. Examples of suitable R_1 or R_2 aralkyl radicals in the above general formula include benzyl, 2-phenylethyl, 2-phenylpropyl, w -xylyl, naphthomethyl, and the like. Examples of suitable R_1 or R_2 cycloalkyl-alkyl radicals include cyclohexylmethyl, cyclohexylethyl, or cyclopentylpropyl, and the like. Examples of suitable R_1 or R_2 aryl radicals include phenyl, naphthyl

and derivatives containing nuclearly substituted chlorine atoms, nitro groups, etc. Examples of suitable R_1 or R_2 alkaryl radicals for substitution in the above general formula are tolyl, xylyl, dimethylphenyl, ethylphenyl, isopropylphenyl, butylphenyl, methylnaphthyl, dimethylnaphthyl, and the like. Examples of suitable R_1 or R_2 cycloalkyl-aryl radicals include cyclohexylphenyl, methylcyclopentylphenyl, cyclohexyltolyl, and the like. Specific examples of selective solvents for employment in the extraction process of the present invention include the following esters of methanethiolsulfonic acid: methyl, ethyl, n-propyl, isopropyl, n-butyl, isobutyl, t-butyl, n-amyl, octyl, dodecyl, hexadecyl, octadecyl; the corresponding esters of ethane-thiolsulfonic acid; the corresponding esters, not however containing more than 20 carbon atoms per molecule, of 1-propanethiolsulfonic acid, 2-propanethiolsulfonic acid, butanethiolsulfonic acid, pentanethiolsulfonic acid, hexanethiolsulfonic acid, octanethiolsulfonic acid, dodecane-thiolsulfonic acid, etc. Other specific examples include methyl benzenethiolsulfonate, methyl-p-toluenethiolsulfonate, ethyl benzenethiolsulfonate, phenyl benzenethiolsulfonate, chlorophenyl chlorobenzenethiolsulfonate, benzyl benzenethiolsulfonate, phenyl 3,5-dinitrobenzenethiolsulfonate, ethyl bis-benzenedithiolsulfonate, etc. It should be understood that we may employ mixtures of esters rather than individual esters. Because of their high selectivity and cheapness, we prefer to employ esters of the above general formula wherein R_1 and R_2 are alkyl radicals containing from one to four carbon atoms.

Although there has been some dispute concerning the chemical structure of thiolsulfonic esters, sometimes called disulfoxides, the consensus of evidence favors the general formula which we have given above. The structures $CH_3SO_2-SCH_3$ and $C_2H_5SO_2-SC_2H_5$ have, for example, been assigned by us on the basis of infrared spectra showing strong absorption bands at 7.6 and 8.8 microns, due to the $-SO_2-$ group and the absence of absorption in the region of 9.1-10.0 microns, indicating the absence of the $-SO-$ group. Structure assignment has also been based upon the discovery by us of a new acid-catalyzed addition reaction of thiolsulfonates to olefins to yield 1,4-sulfonethioethers, rather than the 1,4-disulfoxides which would be the reaction products expected from the symmetrical disulfoxide structure $R_1-SO-SO-R_2$. The selective solvents which we prefer to designate as esters of thiolsulfonic acid are prepared preferably by the oxidation of the corresponding disulfide. They can be prepared non-catalytically with dilute nitric acid, that is, about 40% nitric acid or with hydrogen peroxide as oxidizing agents at ambient temperatures up to about 80° C. Other oxidizing agents may be used. The disulfides also may be oxidized catalytically using air or oxygen as the oxidizing agent and the higher oxides of nitrogen as catalyst as taught in U. S. 2,433,395. The esters of thiolsulfonic acid may also be prepared by other methods well known in the art.

It is not intended to imply that all the thiolsulfonates contemplated for use in this invention are precisely equivalent. However, they are all generally useful and suitable for the purposes of the claimed invention.

The thiolsulfonates defined by the above general formula are either normally liquid or relatively low melting solids and may usually be

used for the purposes of the present invention without auxiliary solvents or diluents. However, because of their solubility in hot water, methanol, ethanol, benzol, etc., it may be desirable to employ the solvents of the present invention together with more or less of such diluents or co-solvents in order to modify the selectivity of the thiolsulfonates, to lower their melting points, or for other reasons. The amount of auxiliary solvents employed can be selected with reference to specific cases; ordinarily, between about 1 and about 20 weight per cent based on the thiolsulfonate will be employed. Anti-solvents or diluents may also be employed in the practice of the present invention. Thus, diluents such as saturated hydrocarbons may be added to the feed stock to be dearomatized or introduced directly into the extraction zone. In the process of the present invention the selective solvent is employed as a liquid, melt or solution and the feed stock may be charged to the process as a liquid or solution.

In general, the extraction operations of the present invention are conducted at temperatures between about -20° C. and about 150° C., the particular extraction temperature depending upon the specific thiolsulfonate solvent, the melting point of the solvent, whether or not it is used alone or with an auxiliary solvent or diluent, the degree and selectivity of extraction sought to be effected, etc.

The volume of selective solvent employed depends, among other things, upon the polycyclic aromatic hydrocarbon and organic sulfur content of the feed stock, the temperature of operation and desired efficiency, but will generally fall within a range of about 0.2 to about 10 volumes of thiolsulfonate per volume of charging stock. Ordinarily, we prefer to employ between about 0.5 and about 2 volumes of solvent per volume of feed stock. Usually, pressures within the range of about 0 to 100 p. s. i. g. are sufficient for this purpose, it being appreciated that the particular pressure necessary in a given case can readily be determined. The extractive process of the present invention is conducted under essentially neutral or slightly alkaline operating conditions.

Numerous hydrocarbon oil fractions derived from petroleum, coal, shale, etc., are known to contain polycyclic aromatic hydrocarbons and organic sulfur compounds whose removal is desired in order to produce refined hydrocarbon oils. Such oils may boil within the boiling range of (and can be generally characterized as) kerosene, virgin gas oil, cracked gas oil, hydroformer bottoms, heater oil, furnace oil, diesel fuel, transformer oil, crude oil, reduced crude oil, visbroken crude oil, lubricating oil, etc. The present refining process can be applied for the purpose of desulfurizing and removing aromatic hydrocarbons and particularly polycyclic aromatic hydrocarbons from various petroleum stocks which are to be subsequently treated in refining or conversion operations in which polycyclic aromatic hydrocarbons, sulfur or sulfur compounds are undesirable, for example, catalytic cracking operations, catalytic reforming operations, catalytic hydroforming operations, catalytic hydrogenation or dehydrogenation in the presence of sulfur-sensitive, readily-coked catalysts, and the like.

The present process may also be applied to the refining of various coal tar fractions and coal tar distillates. In the refining of shale oil fractions the present refining agents serve not only

to remove polycyclic aromatic hydrocarbons and organic sulfur compounds from the feed stock, but also to remove oxygen compounds and nitrogen compounds. It should be understood that the above specific examples of charging stocks which may be refined in accordance with the present invention are illustrative only and are not intended to delimit the field of applicability of the process of the present invention.

The present invention can be carried out in 10 batch, continuous or semi-continuous operating cycles, and in one or more actual or theoretical stages, employing contacting and separation equipment such as has heretofore been employed in the selective solvent refining of petroleum lubricating oil stocks or in effecting the alkylation of isoparaffinic hydrocarbons with olefins in the presence of liquid acid catalysts. It should be understood that the specific equipment employed forms no part of the present invention and that any equipment adaptable for the purposes of contacting the solvent with the hydrocarbon charging stock and thereafter separating an extract phase from the refined charging stock can be employed for the purposes of the invention.

The data in the table afford a comparison of the performance of methyl methanethiolsulfonate in cracked cycle stock extraction with that of silica gel, nitromethane, furfural, dimethylformamide, SO_2 , and diethylsulfoxide, which are among the most highly regarded solvents for the extraction of polycyclic aromatic hydrocarbons from the type of feed stock here under consideration. As a measure of the selectivity of the solvents for the extraction of sulfur compounds, the so-called aromatic selectivity factor (ASF) is determined in accordance with the following equation:

$$ASF = \frac{\text{Percent dearomatization}}{\text{Volume percent extracted}} \times 10^2$$

wherein

Percent dearomatization =

$$\frac{n_{\text{D}}^{20} \text{ feed} - n_{\text{D}}^{20} \text{ raffinate}}{n_{\text{D}}^{20} \text{ feed} - n_{\text{D}}^{20} \text{ silica gel percolate}} \times 100$$

on the basis that silica gel percolation of the feed stock effects complete removal of aromatic hydrocarbons from said stock.

Table

Solvent	Vol. Percent Extract on 100% Treat	Aromatic Selectivity Factor
Silica Gel	16	250
Methyl Methanethiolsulfonate	13	225
Nitromethane	26	200
Furfural	40	150
Dimethyl Formamide	35	220
Sulfur Dioxide	36	160
$\text{C}_2\text{H}_5-\text{SO}-\text{C}_2\text{H}_5$		65

Thus, methyl methanethiolsulfonate was superior in aromatic selectivity to all of the excellent liquid solvents and fell only slightly below the highly selective solid adsorbent silica gel.

The light catalytic cycle stock employed in the examples was derived from the catalytic cracking of West Texas gas oil in the presence of natural clay catalyst and had the following properties:

ASTM distillation

The following examples are intended to illustrate but not necessarily to limit the invention:

Example 1

Light catalytically cracked cycle oil having the properties set forth in the above table was agitated at room temperature and atmospheric pressure with an equal volume of methyl methanethiolsulfonate and the mixture was allowed to settle. The treatment of 50 volumes of cycle stock yielded 58 volumes of a dark-colored bottom or extract layer and 42 volumes of a top or raffinate layer of much lighter color than the feed stock. The raffinate layer was washed with boiling water in order to remove occluded solvent and was then found to have a refractive index (n_{D}^{20}) of 1.4798 and a sulfur content of 0.72 weight per cent. The refractive index of the raffinate was further reduced to 1.4797 after caustic and water washing. The refractive index of the completely dearomatized feed, prepared by silica gel percolation, was 1.4500. Thus, the extraction process effected 36% dearomatization of the feed and 35% desulfurization, with the production of 16% of extract. The aromatic selectivity factor (ASF) was 225.

Example 2

The raffinate obtained by the process of Example 1 was agitated with 1.15 volumes per volume of methyl methanethiolsulfonate to obtain a second raffinate having the refractive index of 1.4691. The second raffinate was agitated with 1.17 volumes per volume of the same solvent to obtain a third raffinate with the refractive index of 1.4626. The third raffinate was agitated with an equal volume of the same solvent to obtain a fourth raffinate with the refractive index of 1.4583. Thus, four batch extraction of the light catalytic cycle oil with methyl methanethiolsulfonate, employed in a total ratio of 4.32 volumes per volume of feed stock, resulted in 83% dearomatization of the feed stock and the production of 32 volume per cent of extract phase.

Example 3

The light catalytically cracked cycle oil employed as the feed stock in Example 1 was agitated for 5 minutes with an equal volume of methyl methanethiolsulfonate which had previously been saturated with ammonia gas and filtered. Within less than 1 minute after agitation had been discontinued, a sharp separation of a clear orange bottom or extract phase and a pale yellow top or raffinate layer was observed to oc-

cur. The amount of extract was 16 volume per cent of the feed stock. The water-washed raffinate phase had a refractive index (n_D^{20}) of 1.4800. While the aromatic selectivity factor in this operation was about the same as that in Example 1, the rate of separation of phases and the colors of both the raffinate and extract phases were all superior to those obtained in Example 1.

Example 4

We have observed that the selectivity of methyl methanethiolsulfonate for monocyclic aromatics is lower than that for polycyclic aromatic hydrocarbons. Thus, the extraction of a synthetic mixture containing equal volumes of benzene and n-heptane with 1 volume per volume of methyl methanethiolsulfonate at room temperature effected 49% dearomatization and the production of 45%, based on feed, of extract phase, corresponding to an aromatic selectivity factor of 111. In another test a 20% solution of amyl benzene in dodecane was extracted with an equal volume of methyl methanethiolsulfonate at room temperature. Dearomatization amounted to 10.6% with an observed aromatic selectivity of 181. An extraction of 20% methyl naphthalene in dodecane gave 56% dearomatization and an observed aromatic selectivity factor of 400. The extractions described in this example, that is Example 4, were carried out in the same manner as the procedure used in Examples 1, 2 and 3 above.

Example 5

As a further example of our process, 5 volumes of a light catalytically cracked cycle oil used as the feed stock in Example 1 were shaken for 5 minutes with 5 volumes of a mixture of alkyl alkanethiolsulfonates (C₁-C₄ range, prepared by the oxidation of a mixture of C₁-C₄ alkyl disulfides with dilute nitric acid) and the resultant mixture was allowed to stand, whereupon it settled to form 6.8 volumes of a bottom or extract layer and 3.2 volumes of a top or raffinate layer which had a substantially lighter color than the feed stock. The refractive index of the raffinate was 1.4708, as against 1.4967 of the feed stock and 1.4500 of completely dearomatized feed stock prepared by percolation of the feed stock through silica gel. Thus, 55.5% dearomatization of the feed stock was achieved with the production of 36 volume per cent, based on feed stock, of extract materials, corresponding to an aromatic selectivity factor of 154.

Example 6

In another test, 5 cc. light catalytic cycle stock with a refractive index of n_D^{20} :1.4967 was shaken for five minutes with 5 cc. of phenyl benzenethiolsulfonate. This latter material was prepared by the oxidation of phenyl disulfide with hydrogen peroxide. It was used in the form of a super-cooled liquid. The mixture was then allowed to stand, upon which it settled to 7.0 cc. dark colored bottom (extract) phase, and 3.0 cc. top (raffinate) phase which had better color than did the feed stock. The raffinate phase contained about 0.1 cc. solvent which was removed by crystallization at low temperatures in the presence of pentane. After removal of the pentane the raffinate had a refractive index of n_D^{20} :1.4684. The refractive index of the completely dearomatized feed (prepared by silica gel percolation) has been found to be n_D^{20} :1.4500. The refractive index of the raffinate corresponds to 61% dear-

matization of the feed with 42% loss of feed into the extract phase.

Example 7

In still another experiment, the above described light catalytic cycle stock was mixed with an equal volume of molten, peroxide-oxidized phenyl methyl disulfide which contained two gram atoms of oxygen per gram mol of product. Intimate contact of the components of the mixture was obtained by agitation at a temperature of 100° C. for a period of five minutes after which, upon standing, phase separation was obtained to give a dark colored extract layer equal to 70% of the total volume and a raffinate layer of light colored oil equal to 30% of the volume of oil and extractant mixture. Extractant was separated from the raffinate by crystallization. The raffinate, substantially free of extractant, mounted to 60% of the catalytic cycle stock used in the experiment, which was 49% dearomatized by contact with phenyl methylthiolsulfonate.

An illustrative process flow and equipment are indicated in the drawing. The hydrocarbon mixture to be extracted, containing polycyclic aromatic hydrocarbons, and optionally organic sulfur compounds, for example, a light cycle stock from silica-alumina cracking of a West Texas gas oil, is passed through valved line 10 into the contacting zone 11. The feed stock is preferably dried and, if it contains hydrogen sulfide, is treated to effect its removal, e. g., by washing with caustic, ethanolamine, N-dimethyl ethanolamine, etc.

We may employ conventional contacting and separation equipment such as has heretofore been employed in effecting selective solvent extraction of lubricating oils, illuminating oils, etc. The contacting equipment may comprise a vertical tower, which is preferably provided with packing or spacing materials to insure thorough contacting of the hydrocarbon feed stock and the thiolsulfonate solvent. Suitable materials of construction for the contacting zone are aluminum and stainless steel, although it should be understood that we may employ other construction materials, for example, glass-, ceramic- or carbon-lined iron towers. Suitable spacing materials comprise shaped fragments, for example Berl saddles or Raschig rings made of carbon, porcelain, glass, aluminum, stainless steel, etc.; stainless steel jack chain; stainless steel or aluminum screens which may be shaped, for example, in the form of Scofield, McMahon or Stedman packing, etc. If desired, the contacting tower may be jacketed or provided with heat exchange coils to permit maintenance of the desired temperature.

In a desirable method of operation, the feed stock is passed into the lower portion of zone 11 against a counter-flow of a thiolsulfonate, for example, methyl methanethiolsulfonate, which is introduced into the upper portion of tower 11 through valved line 12. Diluents, e. g., pentane or hexane, or modifying solvents, e. g. ethanol, may be introduced with the feed stock, the thiolsulfonate solvent or separately through a line not shown, into zone 11. Alkaline conditions during extraction can be maintained by introducing ammonia (gas) into zone 11 (by a line not shown).

The contacting of the thiolsulfonate and hydrocarbon feed stock results in the production of raffinate and extract phases whose common boundary or interface is indicated at 13. The countercurrent extraction zone may be operated

with either the feed stock or solvent as the continuous phase. In the mode of operation, illustrated in the drawing, the extract phase is shown as the continuous phase through which the hydrocarbon feed stock is introduced as the dispersed phase.

The raffinate phase forms a supernatant layer above interface 13 in zone 11, whence it is discharged, together with the diluent employed, from said zone through valved line 14. The raffinate phase is characterized by a substantially reduced content of polycyclic aromatic hydrocarbons and organic sulfur compounds as compared with the feed stock. It should be understood, however, that the raffinate phase may be further treated to reduce its content of polycyclic aromatic hydrocarbons and organic sulfur compounds, if it is so desired. For this purpose, a portion at least of the raffinate phase may be recycled from line 14 by a line (not shown) to re-enter zone 11 with fresh feed stock. Alternatively, or in addition, the raffinate in line 14 may be sent to another contacting zone, identical in all substantial respects with zone 11, for treatment in a second stage with fresh solvent, which may be the same thiolsulfonate or a different thiolsulfonate from that passing into line 12, or may be an entirely different type of solvent, e. g., liquid hydrogen fluoride, HF-BF₃, liquid SO₂, phenol, furfural, dimethylformamide, bis-(beta-chloroethyl) ether, etc. It should be noted that further extraction of the raffinate passing through line 14 with solvents different from the thiolsulfonate passing through line 12 is greatly facilitated by the fact that the thiolsulfonate is substantially insoluble in said raffinate, averting the necessity of special procedures for the removal of thiolsulfonate from said raffinate. Small amounts of thiolsulfonate entrained in the raffinate can be removed by washing with hot water or aqueous hydrochloric acid.

The extract phase, a solution of polycyclic aromatic hydrocarbons and organic sulfur compounds in the thiolsulfonate solvent, is withdrawn from the lower end of tower 11 through valved line 15, whence it is passed into separation zone 16. If desired, a part of the extract phase may be recycled from line 15 to feed line 10 by means of a line not shown in the figure. Zone 16 may be a separating vessel into which hot water or aqueous solvents are introduced by valved line 17, in suitable amounts, e. g., between about 0.5 and about 3.0 volumes per volume of extract, at a temperature between about 20 and about 100° C., to effect the resolution of the extract into an aqueous thiolsulfonate layer and a second layer containing polycyclic aromatic hydrocarbons and organic sulfur compounds (and co-solvent, if any) employed in the extraction operation; said second layer flows overhead through line 18 into settler 19, wherein occluded water is discharged through line 20 and extracted materials through line 21. Methyl methane-thiolsulfonate is soluble to the extent of about 15 g. per 100 g. of water at 65° C. and about 6 g. per 100 g. of water at 20° C.; its solubility in 37.7% hydrochloric acid is about 10 times its solubility in water at the same temperature and the HCl solution of the thiolsulfonate can be resolved into two layers by blowing off HCl gas.

Alternatively, the separation zone 16 may take the form of a distillation vessel, preferably a steam distillation vessel in which the polycyclic aromatic hydrocarbons and sulfur compounds are vaporized and pass overhead, usually as azeotropes with water, through line 18 into a settling

vessel 19, whence the water layer is withdrawn through valved line 20 and extracted materials are withdrawn through valved line 21. The extracted materials may be employed as plasticizers for vinyl resins, natural and synthetic rubber, asphalt, etc.

A bottoms fraction containing the thiolsulfonate is withdrawn from zone 16 through insulated line 22 into a settler 23 provided with weir 24 and cooling coil 25. The temperature of the aqueous solution of thiolsulfonate in settler 23 is reduced to about room temperature or even to a lower temperature, e. g., down to about 10° C. in order to reduce the solubility of the thiolsulfonate solvent in said aqueous phase. If desired, CaCl₂, NaCl, MgSO₄ or other salts may be added to the aqueous phase in settler 23 in order to reduce the solubility of the thiolsulfonate solvent therein. Two immiscible liquid layers are produced in settler 23, one of which is water or an aqueous salt solution and the other of which comprises essentially the thiolsulfonate solvent. The thiolsulfonates are in general of higher specific gravity than water but may be of lower specific gravity than the aqueous salt solutions employed in settler 23. The two layers are separately withdrawn from settler 23 at the appropriate points. For illustrative purposes, in the figure, an aqueous salt solution is shown being withdrawn from settler 23 through valved line 26 and the thiolsulfonate solvent through valved line 27, whence it may be recycled wholly or in part through valved line 28 and manifold 29 to line 12 and thence to extraction column 11. Preferably, at least a portion of the thiolsulfonate solvent is directed from line 27 into a distillation column 30 provided with a heating or reboiler coil 31. Column 30 can suitably be a vacuum still from which steam can be separated from the wet solvent and removed overhead through line 32 into a barometric condenser 33. The dried solvent is discharged as bottoms through line 34 into manifold 29 for recycle to the extraction zone 11.

Alternatively, the recycle stream of solvent may be dehydrated in column 30 by azeotropic distillation of water therefrom with various azeotroping agents, e. g. benzene, toluene, n-heptane, ethyl acetate, etc.

Although the drawing represents a continuous countercurrent extraction operation, it will be apparent that the process of the present invention is amenable to batch processing, multi-unit operation, concurrent flow of solvent and feed stock, the use of knot-hole or other mechanical mixers for feed and solvent in series with one or more settling zones and other variations that will no doubt occur to those skilled in the art without departing from the spirit of this invention.

In our copending United States application for Letters Patent, Serial Number 244,374, filed of even date herewith, we have described and claimed the selective extraction of organic sulfur compounds from their mixtures with hydrocarbons by the employment of the aforesaid esters of thiolsulfonic acids.

Having thus described the process of our invention, what we claim is:

1. A process for the extraction of an aromatic hydrocarbon from a hydrocarbon mixture containing the same, which process comprises contacting said mixture with an ester of a thiolsulfonic acid containing 2 to 20 carbon atoms per molecule and separating a raffinate phase

11

from an extract phase comprising said ester and said aromatic hydrocarbon.

2. The process of claim 1 wherein the aromatic hydrocarbon is polycyclic.

3. The process of claim 1 wherein said mixture comprises a cracked gas oil containing polycyclic aromatic hydrocarbons.

4. A process for the extraction of a polycyclic aromatic hydrocarbon from a hydrocarbon mixture containing the same, which process comprises contacting said mixture with an ester of a thiolsulfonic acid containing 2 to 20 carbon atoms per molecule in liquid condition, separating an extract layer containing said ester and said polycyclic aromatic hydrocarbon, selectively extracting said ester from said extract layer with an aqueous extractant at a temperature between about 20° C. and about 100° C. to produce an aqueous ester, drying said aqueous ester and recycling the resultant dried ester to further contact with said mixture.

5. The process of claim 4 wherein said ester has the formula $R_1SO_2-SR_2$ wherein R_1 and R_2 are alkyl radicals containing 1 to 4 carbon atoms.

6. The process of claim 4 wherein said mixture comprises a cracked gas oil and said ester has the formula $R_1SO_2-SR_2$ wherein R_1 and R_2 are alkyl radicals containing 1 to 4 carbon atoms. 25

12

7. A process for the extraction of a polycyclic aromatic hydrocarbon from a hydrocarbon mixture containing the same, which process comprises contacting said mixture with an ester of a thiolsulfonic acid containing 2 to 20 carbon atoms per molecule in liquid condition, separating an extract layer containing said ester and said polycyclic aromatic hydrocarbon, selectively extracting said ester from said extract layer with an aqueous extractant at a temperature between about 20° C. and about 100° C. to produce an aqueous ester, drying said aqueous ester and recycling the resultant dried ester to further contact with said mixture.

8. The process of claim 7 wherein said ester has the formula $R_1SO_2-SR_2$ wherein R_1 and R_2 are alkyl radicals containing 1 to 4 carbon atoms.

9. The process of claim 7 wherein said mixture comprises a cracked gas oil and said ester has the formula $R_1SO_2-SR_2$ wherein R_1 and R_2 are alkyl radicals containing 1 to 4 carbon atoms.
